CARTON BLANK

Peter Ellice Elford, 3 Wincroft Road, Caversham,
Reading RG4 7HH, England

Filed Sept. 21, 1973, Ser. No. 399,522

Claims priority, application Great Britain Mar. 28, 1973

Term of patent 14 years

Int. Cl. D9—03

U.S. Cl. D9—245

FIG. 1 is a plan view of a carton blank showing my new design.

FIG. 2 is an edge view thereof taken from arrow A of FIG. 1; and

FIG. 3 is an edge view thereof taken from arrow B of FIG. 1.

I claim:

The ornamental design for a carton blank, substantially as shown.
